(57) **CLAIM**

The ornamental design for a side table, as shown and described.

DESCRIPTION

FIG. 1 is a top plan view of a side table showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a bottom view thereof;

FIG. 7 is a top plan view thereof with a left chair leg bracket being extended;

FIG. 8 is a bottom view thereof with the left chair leg bracket being extended;

FIG. 9 is a fragmentary sectional view through the left chair leg bracket, the same being taken along the plane 9-9 of FIG. 7;

FIG. 10 is a sectional view through the left chair leg bracket, the same being taken along the plane 10-10 of FIG. 8;

FIG. 11 is a left side elevational view thereof, with the left chair leg bracket extended;

FIG. 12 is a right side elevational view thereof, with the left chair leg bracket extended; and,

FIG. 13 is a front perspective view thereof.

The broken line showings form no part of the claimed design and the right chair leg bracket may be extended in lieu of the left chair leg bracket, with the views corresponding to those of FIGS. 7-11 appearing as mirror images.
